UNITED STATES PATENT OFFICE

SVEND M. JORGENSEN, OF ELIZABETH, NEW JERSEY, ASSIGNOR TO THE SUPERHEATER COMPANY, OF NEW YORK, N. Y., A CORPORATION OF DELAWARE

DESUPERHEATER

Application filed June 18, 1928. Serial No. 286,367.

This invention relates to apparatus known as desuperheaters, of the type employed in power plants where superheated steam is mainly used but where in addition it is desired for various purposes to have a supply of steam of lower temperature. As heretofore constructed such apparatus has been of two general types known as "direct contact" and "indirect contact". In the former, a jet, or jets, of water are injected directly into a body of steam, while in the latter the steam is led through pipes or coils submerged in a body of water; such passage of the steam lowering its temperature while simultaneously raising the temperature of the water and causing steam of lower temperature to be generated therefrom.

This invention relates primarily to direct contact desuperheaters and has for its principal object to improve such apparatus by providing means for producing an effective circulation of the body of water in which the steam coils are submerged.

Other objects are to provide a new and improved method of desuperheating steam which comprises features of both direct and indirect contact desuperheating, and new and improved apparatus for carrying out said method.

The above and other objects will appear more fully from the following more detailed description and by reference to the accompanying drawings forming a part hereof and wherein Fig. 1 is a side elevation partly in section of a satisfactory constructional example of a desuperheater constructed in accordance with the principles of my invention, and Fig. 2 is a section on the line 2-2 of Fig. 1.

I have shown the invention as applied to an existing type of indirect contact desuperheater which comprises a cylindrical drum or casing 10, closed at the top, by a head 11 and having at the bottom thereof a header 12. A tube sheet 13 separates the header 12 from the interior of the drum 10. The header 12 is provided with a flanged inlet spud 14 and a similar outlet spud 15. The spud 14 has connected to it a pipe or conduit 16 which leads to the main boiler or other source of

supply of superheated steam; a valve 17 is interposed between the conduit 16 and spud 14. Extending diametrically across the header 12 is a baffle 18 which shuts off direct communication or flow of the fluid from the inlet to the outlet of the header. 55

A number of U-shaped tubes 19 have their ends secured in the tube sheet 13 and in communication with the interior of the header 12 upon opposite sides of the baffle 18. 60

Water is introduced into the interior of the drum 10 by means of a pipe 20 preferably located towards the lower end of said drum. It will be understood that when the drum is filled to the proper level with water, preferably above the top end of the tubes 19, and when superheated steam is fed to the desuperheater through the conduit 16, such superheated steam passing into the header 12 will rise through the left hand sides of the tubes 19 and will flow outwardly from the right hand sides of said tubes upon the right hand side of the baffle 18 and will pass out of the header through the outlet spud 15. In its passage through the tubes, which are submerged in water, the temperature of the superheated steam will be greatly reduced and steam of lower temperature will be generated from the water within the drum 10. 70

The steam rising from the water in the drum 10 passes out through the top head 11 to a pipe 21, one end of which, as shown in Fig. 1 of the drawings, is connected to an aperture of the head 11 and the other end of which is connected to a T fitting 22, which 80

fitting serves to connect to the outlet spud 15 a conduit 23. It will thus be seen that the steam generated from the water in the container is mixed or blended with the steam that has passed through the tubes 19 and it 90 will be understood that this mixture of steam is led to the place of use by the pipe or conduit 23. The constructional details so far described are those of an existing desuperheater of the indirect contact type and such 95 constructional details form no part of the present invention except insofar as they are illustrative of a satisfactory construction in which the principles of the present invention may be embodied. 100

In accordance with the present invention, a desuperheater of the type so far described, or any other suitable construction, may be employed in conjunction with the features now to be described. In the indirect contact desuperheaters as heretofore constructed, all of the superheated steam is passed through tubes or coils such as the tubes 19 and out of direct contact with the water in which said tubes are submerged. In accordance with the principles of the present invention, part of the superheated steam, and preferably a minor part thereof, is injected directly into the water in which the tubes are submerged. This can be done in many ways and therefore the constructional details of the means shown in the drawings for accomplishing this purpose are to be considered as merely illustrative and not as limiting the invention to the details of such means selected for illustration. As shown in the drawings a small pipe 25 is connected with the conduit 16 for tapping a portion of the superheated steam and leading it to the interior of the drum 10; the steam tapped through the pipe 25 being by-passed around the header 12 as clearly shown in Fig. 1 of the drawings. The pipe 25 communicates at the drum end with a plurality of nozzles 26 each of which 30 nozzles project into a short tube 27. Each tube 27 is connected by means of an L 28 with one end of a curved pipe 29 the other end of which pipe is connected to the drum by a flanged fitting 30 and communicates 35 with the interior of the drum. Any desired number of nozzles 26 and tubes 27 may be employed. For the purpose of the present disclosure I have shown two of such nozzles and tubes. It will be understood that each tube 40 is connected through a pipe 29 to the interior of the drum.

The tubes 27, as shown in Fig. 2, terminate short of the longitudinal center line of the drum and rearwardly of the ends of a pair 45 of vertical baffles 31 which, as shown in Fig. 2, extend substantially radially of the drum.

The inner ends of the baffles 31 are spaced apart to provide a passage for the steam injected through the nozzles 26, and the outer 50 edges of the baffles are spaced from the inner side walls of the drum.

The operation of the apparatus as will be readily understood is as follows: The major portion of the steam to be desuperheated passes through the conduit 16 to the header 12 and flows through the tubes 19 to the outlet 15 and conduit 23, as hereinbefore described. The steam tapped through the pipe 25 is projected from the nozzles 26 into the tubes 27. These tubes however are in communication with the interior of the drum through the pipes 29 and their connections. The steam issuing from the nozzles produces an injector effect which causes the water in 65 the drum to be drawn through the pipes 29

and to be projected through the tubes 27 back into the interior of the drum. The injector effect causes a jet of mingled steam and water, or steam of reduced temperature, to be projected into the interior of the drum through the passageway or space formed between the inner ends of the baffles 31. The effect of such jet is to produce a circulation of the water within the drum, said water passing about the outer ends of the baffles 31 into the zone located between the baffles and in which the tubes 27 are located.

It will be seen from the above that a very effective and relatively rapid circulation of the water contained in the drum is produced by the injection of a minor portion of the steam directly into the water and that although this part of the steam is diverted or taken from the main portion thereof, such diversion is not detrimental or objectionable but in fact is a distinct advantage because of the more rapid heat transfer which occurs between the steam and the water into which said steam is directly injected than between the steam which passes through the coils out of direct contact with the water.

It will be understood that many changes, variations and modifications of the constructional details of the apparatus selected for illustration may be made without departing from the principles of the invention.

I claim:

1. The method of desuperheating superheated steam which consists in continuously passing a portion of the steam to be desuperheated in heat exchange relationship with a body of water but out of direct contact therewith, while simultaneously injecting another portion of said steam directly into said water and then mixing with the superheated steam the steam generated from said water, by the heat imparted thereto by said superheated steam.

2. The method of desuperheating superheated steam which consists in continuously passing a major portion of such steam in heat exchange relationship with a body of water but out of direct contact therewith, while simultaneously injecting a minor portion of said steam directly into said water and then mixing with the said major portion of said steam the steam generated from said water.

3. The method of desuperheating superheated steam which consists in continuously passing a major portion of the steam to be desuperheated in heat exchange relationship with a body of water but out of direct contact therewith, while simultaneously injecting a minor portion of said steam directly into said water and employing the steam so injected for producing a continuous circulation of such water and then mixing with the said major portion the steam generated from said water.

4. In an apparatus of the character described, a container adapted to hold a body of water, a plurality of conduits in said container submerged in said water, means for admitting superheated steam to said conduits and means for injecting superheated steam directly into said body of water.

5. In a desuperheater, a drum adapted to contain a body of water, a plurality of conduits located in said drum and submerged in said water, means for supplying water to said drum, said conduits being connected with a source of superheated steam, and a plurality of nozzles also connected with said source for injecting superheated steam directly into said water.

6. In a desuperheater, a drum adapted to contain a body of water, a plurality of conduits located in said drum and submerged in said water, means for supplying water to said drum, said conduits being connected with a source of superheated steam, a plurality of nozzles also connected with said source for injecting superheated steam directly into said water, and baffles located in said drum adjacent to said nozzles for causing the jets of steam projected from said nozzles to produce a circulation of the water within said drum.

7. In a desuperheater, a drum adapted to contain a body of water, a header located at one end of said drum, said header being provided with an inlet and an outlet, a conduit connecting said inlet with a source of superheated steam, a baffle in said header for preventing direct communication between said inlet and outlet, a plurality of conduits having their ends in communication with said header upon opposite sides of said baffle, a plurality of nozzles projecting into said drum externally of said conduits, and a pipe for leading superheated steam from said inlet conduit to said nozzles.

8. In a desuperheater, a drum adapted to contain a body of water, a plurality of conduits submerged in said water, means for connecting said conduits with a source of superheated steam, a plurality of tubes projecting into said drum, each of said tubes having a jet nozzle therein, and means for connecting said nozzles with a source of superheated steam.

9. A desuperheater as set forth in claim 8 in which each of said tubes is open at its inner end to the interior of said drum and is connected at its outer end by a connecting pipe with a different point or zone of the interior of the drum.

10. In a desuperheater, a drum adapted to contain a body of water, a plurality of conduits submerged in said water and through which superheated steam is adapted to be passed out of direct contact with said water, a plurality of open ended short tubes secured at spaced intervals to the side walls of said

drum and projecting into the interior thereof, the inner ends of said tubes terminating short of the center of said drum, a nozzle projecting into the outer end of each of said tubes and terminating short of the inner end thereof, and a circulating pipe for each of said tubes, each of said pipes having its one end connected with the outer end of its respective tube and its other end leading to a different point on the side wall of said drum and communicating with the interior of the drum.

11. In a desuperheater, a drum adapted to contain a body of water, a plurality of conduits located in said drum and submerged in said water, means for connecting said conduits with a source of superheated steam, baffle means located in said drum adjacent to the center thereof but out of contact with the side walls of said drum so as to permit circulation of water between said baffle means and the side walls of the drum, and a plurality of nozzles connected with said source of superheated steam for projecting such steam into said water and for producing a circulation of the water about said baffle means.

In testimony whereof I have hereunto set my hand.

SVEND M. JORGENSEN.
